UNITED STATES PATENT OFFICE.

SIGMUND L. LEDERER, OF PROVIDENCE, RHODE ISLAND.

DESIGN FOR A CHARM.

SPECIFICATION forming part of Design No. 13,399, dated November 7, 1882.

Application filed October 3, 1881. Renewed September 29, 1882. Term of patent 7 years.

To all whom it may concern:

Be it known that I, SIGMUND L. LEDERER, of the city and county of Providence, State of Rhode Island, have invented and produced a new and original Design for Charms, of which the following is a full, clear, and exact description of the same, reference being had to the accompanying drawings, forming part of this specification.

10 Figure 1 is a perspective view of my newly-designed charm, consisting of two horizontal bars united by two links, the horizontal bars extending beyond the side-links, the whole forming a frame for a stone or jewel. Fig. 2
15 is a view of the connecting-link, and Fig. 3 is a sectional view of the charm.

In the drawings, *a* is the stone or jewel; *b*, the horizontal bars; *c*, the side links, and *d* any ornament by which the charm is suspended.

Having thus described my invention, I claim 20 as new and desire to secure by Letters Patent—

The design for a charm, which consists in a stone or jewel set in a frame made of two round horizontal bars and two vertical links, the bars extending beyond the links, as de- 25 scribed.

SIGMUND L. LEDERER.
